UNITED STATES PATENT OFFICE.

AARON C. GIFFORD, CHARLES H. GIFFORD, AND JESSE H. GIFFORD, OF NEW YORK, N. Y.

GYMNAStic APPARATUS.

SPECIFICATION forming part of Letters Patent No. 244,388, dated July 19, 1881.

Application filed December 29, 1880. (No model.)

To all whom it may concern:

Be it known that we, AARON C. GIFFORD, CHARLES H. GIFFORD, and JESSE H. GIFFORD, of New York, in the county of New York and 5 State of New York, have invented a new and useful Improvement in Gymnastic Apparatus, of which the following is a specification, reference being had to the accompanying drawing.

The invention relates to an improvement in 10 gymnastic apparatus, as hereinafter set forth.

Heretofore in that class of gymnastic appliances known as "rowing-machines" and "pulling-weights" a difficulty has been experienced by reason of the fact that the return of the 15 weights exerts a tension upon the operator almost equal to the strain required to draw the same upward. Usually, except in parlor rowing-machines, the weights connected with the arms have been arranged in vertical guides or 20 suspended in a vertical position by ropes or otherwise. When the handles are drawn toward the operator the weights are caused to ascend and act as a resistance to the power applied. After the forward stroke of the handles has been accomplished the return of the 25 weights by their own specific gravity retracts the handles and operates to draw the arms and body of the attendant forward. When heavy weights are employed their return down 30 the guides is so sudden and rapid that the body of the attendant is brought forward so quickly that the chest and other parts are frequently strained in holding in the handles of the machine; besides, it will be observed, there is no 35 relaxation of the muscles, force being required to draw the weights upward, and also to prevent them falling as dead-weights.

To remedy these objections, and to produce a means whereby the weights may have a 40 gradual return without effecting a strain upon the attendant, is the object of our invention. This we have partially accomplished by allowing the weights to travel on inclined tramways; but these only overcome the objections in a 45 limited degree.

In the accompanying drawing we have illustrated the invention, in a side view, of an apparatus that may be employed as either a rowing-machine or for pulling weights.

50 A indicates the base of the apparatus or ma-

chine; B, an upright; C, a tramway inclined from near one end of the base to the upper portion of the upright. D is the weight resting upon the tramway and secured to the end of a rope, E, which passes upward over a pulley, F, journaled in the upper end of the upright C; thence it extends downward under the pulley G and forward a suitable distance to be grasped by the operator.

The devices above referred to are shown in 60 a patent heretofore granted to us.

Our present improvement consists in providing the rope H and counterpoise I in the manner shown with sufficient accuracy in the drawing. One end of the rope H is attached 65 to the weight D, while the other end passes upward over the pulley a, secured upon the standard or upright C, thence downward along the side thereof a suitable distance, and has attached to its end the counterpoise I. The 70 weight of the counterpoise I will vary according to the wish of the operator and the size of the weight D. The effect of the counterpoise I is to retard the return down the tramways of the weight D, and thereby relieve the 75 strain on the operator caused by holding back the weight, and to prevent the body being jerked forward by the sudden fall of the weights. A vigorous operator would probably wish but a slight retard of the weight D, and 80 in this case a small counterpoise will be employed, which, of course, will vary according to circumstances, the heft of the weight D, the inclination of the tramways, &c. For a less robust person it will be desirable to attach a 85 larger counterpoise, in order that the weight D may return gradually and the strain on the operator be entirely relieved. It requires but a slight weight, arranged as shown, to retard the downward movement of the weight 90 D, while on the upward movement it has but a slight effect in reducing the effort necessary to elevate the weight D. We will preferably employ two weights D, with two ropes and standards, in order that both arms may be exercised simultaneously.

What we claim as our invention, and desire to secure by Letters Patent, is—

1. In an apparatus for exercising or other purposes, a weight secured to the end of a rope 100

or chain, and adapted to be elevated or lowered by force applied to the rope or chain, in combination with a counterpoise connected with the weight, and traveling in a reverse direction thereto, substantially as set forth.

2. In an exercising apparatus, the weight D, resting upon the tramways C and attached to the rope E, in combination with the counterpoise I, substantially as set forth.

10 In testimony that we claim the foregoing

improvement in gymnastic apparatus as above described we have hereunto set our hands this 24th day of December, 1880.

AARON C. GIFFORD.
CHAS. H. GIFFORD.
JESSE H. GIFFORD.
